UNITED STATES PATENT OFFICE.

MORONI DANIEL FERRIN, OF SALT LAKE CITY, UTAH.

FLYING-MACHINE.

1,107,921.

Specification of Letters Patent. Patented Aug. 18, 1914.

Application filed November 29, 1912. Serial No. 734,075.

To all whom it may concern:

Be it known that I, MORONI DANIEL FERRIN, a citizen of the United States, and a resident of Salt Lake City, in the county of Salt Lake and State of Utah, have invented a new and useful Improvement in Flying-Machines, of which the following is a specification.

My present invention relates to flying machines, and more particularly to that type of flying machine which comprises side wings movable up and down and constituting the sole means by which the machine is enabled to rise from the ground and proceed either forward or backward.

The object of my invention is to provide a flying machine of the above type which will effectively perform all of the essential movements of the more common types of flying machines, and which will be safe, steady and comfortable in use.

A further object of my invention is to provide a flying machine having a lower portion provided with a shock absorbing landing arrangement and a frame and operating mechanism which is so associated with the said landing arrangement as to be movable to constantly face the wind when standing on the ground in a manner similar to that of the well known weather vane.

A still further object of my invention is to provide a flying machine comprising a lower portion adapted to uniformly maintain a perpendicular position, and an upper portion containing the operating wings, and so connected as to be movable by means which are themselves simply and readily operable, to inclined positions whereby the machine may be adapted to proceed either forwardly or rearwardly dependent upon the direction of such inclination.

Further objects and the resulting advantages of my present invention, will be apparent from the following description, in which reference is made to the accompanying drawings, forming a part of this specification and in which,

Figure 1 is a side elevation of my improved flying machine; Fig. 2 is a front elevation thereof; Fig. 3 is a partial front elevation and vertical section, on an enlarged scale, with the extreme upper and lower portions broken away; Fig. 4 is a longitudinal section through the upper wing carrying portion of the machine with the forward and rear portions broken away; Fig. 5 is a

top plan view of those parts illustrated in Fig. 4; Fig. 6 is a horizontal sectional view looking downwardly into the frame and taken substantially on the line 6—6 of Fig. 1; Fig. 7 is a detail side elevation, partly broken in section, illustrating the connections of the rudder; Fig. 8 is a detail transverse section through the parts shown in Fig. 7 and taken substantially on the line 8—8 of said figure; Fig. 9 is a detail perspective view of one of the crank shaft supporting brackets to be hereinafter specifically referred to; and Fig. 10 is a detail sectional view, on an enlarged scale, illustrating the connections of one of the legs of the landing device and its outside spring.

Referring now specifically to these figures, 1 indicates the motor which is firmly seated upon the platform 5 and which may be of any type suitable for transmitting power to the driven wheels 8. I prefer, however, that this motor shall be capable of control by means of levers indicated at 1^a and 1^b, one of which may be a speed control lever and the other a clutch control lever, these levers being placed upon one side of the motor closely adjacent to the operator's seat 5^b.

The platform 5 upon which the motor 1 is firmly seated, may be of any desired shape, although I have shown it in the drawings, and particularly in Fig. 6, as of a hexagonal shape with an upright post 6 at each corner, these posts serving to support the wire side 6^a of the car or basket. As clearly indicated in Fig. 6, the platform is so arranged that a pair of the posts 6 are in the same plane with the longitudinal axis of the machine, each of these posts carrying a pulley 7 at its upper end.

The motor 1 seats between and is secured to, the spaced uprights 2, the driven wheels 8 being mounted upon a shaft having bearings in the said uprights. To the upper ends of the uprights 2 are pivotally connected the lower portions of spaced uprights 4, the pivotal connection being formed by a transverse member 4^a, said member 4^a supporting a pair of spaced sprocket wheels 3, connected by chains 11 to the driven wheels 8 before mentioned. The member 4^a also serves to support a sprocket wheel 9 intermediate the wheels 3 and connected, by a sprocket chain 12, to the upper sprocket wheel 10 which is mounted upon a transverse shaft 10^a as clearly in-

dicated in Figs. 1 and 3. At the outer ends of the shaft 10^a last mentioned, which project beyond the uprights 4, are small bevel gears 13 which are in mesh with larger bevel gears 14 secured upon the crank shafts 15, which latter extend longitudinally of the machine upon opposite sides of the upper portions of the uprights 4 and are provided with cranks 15^a, set at angles of 120 degrees with respect to one another, as clearly shown. The cranks 15^a are connected, by connecting rods 16, to the wings 17, 18 and 19, at points a short distance from the inner ends of the latter, the extreme inner ends of which are journaled upon a central longitudinal shaft 20, supported in a plane above that of the crank shaft by means which will be hereinafter described. Thus when the shafts 15 are rotated through the connections just mentioned, the several wings 17, 18, 19 are forced to move up and down in a manner much similar to the movements of the wings of a bird in flight. It will be noted by reference to Figs. 1 and 2 that there are ten of the wings in all, these wings being arranged in sets, of which the outer set, comprising two side wings at the extreme forward and rear portions of the machine, are indicated by the numeral 17, the intermediate set comprising side wings next to those constituting the outer series 17, being indicated by the numeral 18, and the central set comprising only a single pair of wings which, however, are equal in area to the wings of each of the sets 17 and 18, being indicated by the numeral 19. The several sets of wings are so connected to the crank shaft that the wings of each set or series work in unison. The wings 17, 18 and 19 are further provided with downwardly opening valves which will automatically open when the wings are forced upwardly and close when the wings are forced downwardly. The valves are formed by the peculiar structure of the wings themselves, each of these wings consisting of a substantially rectangular frame 17^a having a foraminous covering and provided upon its lower surface with a plurality of fabric strips 17^b which are secured along one edge to the foraminous covering, their opposite edges being free. Extending angularly and downwardly from the under surface of each of the wings are also a series of rods 17^c which limit the downward movement of the free edges of the strips 17^b. Thus when the wings are descending, the strips 17^b will be held against the foraminous covering before mentioned whereby to prevent air from passing through the wings, while when the wings are ascending, the free edges of the strips will move downwardly against the rods 17^c and thus permit air to pass practically unresisted through the wings.

The shafts 15 and 20 are connected by a plurality of substantially triangular braces 21, in the lower portions of which the first-mentioned shafts are journaled, and the upper portions 21^a of which, as clearly indicated in Fig. 1, are bent angularly and their upper ends joined together in pairs so as to provide spaces along the shaft 20, within which the inner ends of the wings are connected. The shafts 15 are further braced by means of the members 30 which are secured to outstand upon opposite sides of the uprights 4, and one of which is shown in detail in Fig. 9, and also by means of the framelike brace 28^a, portions of which are secured to the said uprights as shown in Fig. 1. Each of the braces 30 is provided with parallel joined sides 30^a, the outer edges of which are provided with alined slots 30^b through which the respective shaft 15 extends, as clearly indicated in Fig. 3. As also indicated in this last-mentioned figure, and even more clearly in Fig. 1, the bevel gear 14 of the crank shaft is disposed between the sides 30^a of the brace 30, and to this end one side 30^a is apertured at 30^c in order that the complementary gear wheel 13 may project into engagement with the gear wheel 14 previously mentioned. The superstructure of the machine including the shafts 15 and 20, the wings, and the several connections between these parts, is also braced by guys 32 extending between the upper connected ends of the portions 21^a of braces 21 and the upper extremities of the uprights 4 above the shaft 20, and also by guys 33 below, which are connected between points of a longitudinal channel beam 29 and the lower extremities of the uprights 4, as indicated in Fig. 1, said channel beam 29 being connected to, and extending along the lower portions of the several braces 21.

A ball bearing joint, indicated at 36, is formed between the platform 5 and the upper portion 44 of the landing device, these parts being connected by a centrally disposed king bolt 48 whereby the entire machine may turn upon the landing device, when at rest, so as to uniformly face the wind under the effect of the air current upon the rudders to be described.

A pair of rudders, indicated at 37 and 38, are disposed in the rear of the car or basket and mounted upon a bracket 39 which is secured to the rear post 6. These are hingedly connected at 38^a to members 38^b whereby they may swing in horizontal planes, the said members 38^b being in turn secured to a transverse shaft 40 which is journaled through the rear extremity of the bracket 39 and provided with an extension 40^a which is movable between the upper and lower portions of the said bracket whereby to limit the rotative movement of shaft 40. The rudders may thus move up and down for a

purpose to be hereinafter described, and may be swung horizontally by means of their connections 42 with foot pedals 43 mounted on the platform 5 immediately in front of the operator's seat 5^b. The upper and lower edges of the rudders are flanged for the purpose of stiffening and strengthening the same and also permit of their ready guidance to angular or inclined positions within the limits of movement of the member 40^a whereby they may uniformly maintain positions parallel to the air current when the lower portion of the machine swings slightly as it will be very likely to do in use.

15 The upper portion 44 of the landing device before referred to is provided upon its under surface with recesses extending inwardly from its edge and in which are pivoted the upper beveled ends of divergent dependent legs 45. The pivots 46 of legs 45, as particularly indicated in Fig. 10, are so arranged that the said beveled ends of these legs prevent the same from inward movement to perpendicular position, and the 20 several springs 47 and 49 tend to resist outward movement or spreading of the legs, springs 47 being secured to the upper portion 44 of the landing device and being in the nature of bow springs, the free outer 25 ends of which bear inwardly against the outer surfaces of the several legs, and springs 49 being in the nature of retractile coil springs which are secured between points upon the inner surfaces of the legs and the 30 lower ends of the guying bolt 48. Thus when the machine lands upon the ground, the legs 45 will spread and take up the shock, after which the legs will be gradually drawn to their normal positions through the further 35 action of the springs.

40 It is intended that the platform 5, in addition to supporting the operator, shall have suitable seats or benches 5^a for passengers, and space and equipment for containing such cargo as the machine may be adapted to support.

45 Adjacent the lower ends of the uprights 2, is a framelike brace 25 which may be clearly seen in Fig. 1 and which is adapted to support the steering wheel 26, and the shaft thereof around which are wrapped the ends of the tilting ropes or cables 27 and 28, these ropes being reeved over pulleys 29^a supported between the uprights 2, and thence beneath the pulleys 7 beforementioned, from which they extend upwardly to the forward and rear ends of the channel iron 29, forming a part of the superstructure as before described.

50 60 Thus from the foregoing, it may be readily seen that by virtue of the rudders 37 and 38, when in their normal positions, as indicated in Fig. 6, the flying machine proper may uniformly maintain itself in a position facing the wind, inasmuch as it is mounted to

freely rotate with respect to its landing frame upon which it rests at this time. It will be further seen that the machine proper is in two general divisions, the first of which includes the supporting basket for the operator, the passengers, the cargo and equipment, and the uprights 2, the other division including the uprights 4 and the superstructure which is readily tiltable to a desired degree of inclination either forwardly or rearwardly through the tilting ropes or cables 27 and 28, under the control of the operator's wheel 26, as clearly described.

Starting from the position shown in Fig. 1 when the crank shafts 15 are rotated through their connections with the motor 1, as previously described, the wings 17, 18 and 19 are swung upwardly and downwardly at a speed which is intended to be regulated by the levers 1^a and 1^b, and the machine is caused to rise in a perpendicular line. When the desired height has been reached, and the speed of movement of the wings reduced until their ascending power equals the combined weight of the machine, the same will be maintained at a standstill in mid air. When it is desired to proceed forwardly or rearwardly, the superstructure contained in the wings is tilted forward or backwardly, as the case may be through actuation of the tilting ropes 27 and 28, and when the speed of movement of the wings is again increased, the machine will maintain its altitude and move in a horizontal line, or at an ascending or descending angle as desired, being guided to the right or left by using either the right or left rudder. The motion of the machine is to be stopped by gradually reducing the tilt of the superstructure containing the wings, and at the same time drawing both of the rudders 37 and 38 to positions at right-angles to the longitudinal axis of the machine which will cause them to catch the air, and at the same time effectively prevent the lower portion of the machine from swinging or vibrating to and fro. In this way, a steady equal reduction in speed may be effected. When the machine has been stopped in mid-air, a safe landing may be effected by correcting the tilt of the superstructure and diminishing the power to a point wherein the ascending power of the wings is less than the weight of the machine, thus permitting the machine to descend at a desired speed to the earth, in a perpendicular line, the landing arrangement permitting the machine to alight safely and with little or no shock.

If it is so desired, a flexible parachute of the ordinary type may be normally carried in a folded position around the upper portions 4^b of the uprights 4, above the plane of the wings, and adapted to be released when needed so as to automatically assume

an operative position, in which the parachute connections with the said upper portions of the uprights 4, will appear as indicated at 50 in Figs. 1 and 2.

5 I claim:—

1. A flying machine of the character described comprising a main frame, spaced uprights rigidly connected to, and rising from said main frame, a superstructure consisting of spaced upright members pivotally connected adjacent their lower ends to the upper ends of the said main frame uprights, and a horizontal member rigidly connected to the upright members intermediate the ends of the latter, a central shaft mounted parallel with and above the horizontal member, operating wings having their inner ends movably connected to the said shaft and arranged to swing in vertical planes, crank shafts mounted below and at opposite sides of the horizontal member and having connection with the said operating wings, braces connected to the vertical and horizontal members of the superstructure for supporting the said shafts, connections between the ends of the superstructure and the main frame for tilting the former with respect

to the latter, a motor mounted in the main frame, and driving connections between the motor and the crank shafts including transmission gears concentric with the pivotal connection between the main frame and the superstructure, all for the purpose described. 30

2. A flying machine of the character described comprising a main frame, a superstructure carried by the main frame consisting of vertical and horizontal supporting members, and a plurality of braces, a shaft mounted horizontally in the superstructure, 35 operating wings carried by the shaft and arranged to swing in vertical planes, means for actuating the said wings, means for tilting the superstructure with respect to the main frame, a landing frame with which the main frame has swivel connection and a rudder mounted on the main frame in order that the latter and the superstructure may be normally maintained in position facing the wind. 40
